UNITED STATES PATENT OFFICE.

JOHN VALENTINE, OF BUFFALO, NEW YORK.

IMPROVEMENT IN HORSE-POWERS.

Specification forming part of Letters Patent No. 119,954, dated October 17, 1871.

To all whom it may concern:

Be it known that I, JOHN VALENTINE, of the city of Buffalo, in the county of Erie and State of New York, have invented a certain Improvement in Horse-Powers, of which the following is a specification:

My improvement relates to that class of horse-powers in which a stationary toothed rim is fastened to the bed of the machine, above which is arranged the rotating frame provided with a pinion which engages with the said rim and transmits, through suitable gear, motion to a central vertical shaft. This toothed driving-rim has usually been secured, by bolts, directly to the wooden bed pieces of the machine. The yielding character of the wood permits these bed pieces to spring under a sudden strain, which movement, being communicated to the toothed rim, causes the same to bind with the pinion that engages therewith. My invention consists: First, in the combination, with the central shaft of a horse-power, of the driving toothed rim cast with hub-like projections and a cast-iron bridge-tree, the arms of which are formed with sockets to receive the ends of the hubs of the driving-rim. Second, in the arrangement, with the toothed rim, bridge-tree, and bed of the machine, of a bolt which firmly secures the said parts together.

In the accompanying drawing, Figure I is a sectional elevation, and Fig. II a plan of my improvement inverted.

Like letters of reference designate like parts in each of the figures.

A is the spur-rim; *a a*, a series of hubs cast with and projecting downward from the under side of the rim. They are preferably made hol-

low, as shown in the drawing. B is the bridge-tree, cast with four arms, Fig. II, the ends of which, on their upper side, are formed with sockets *b* to receive the ends of the hubs *a*, as represented in Fig. I. C C are the two pieces which constitute the bed of the machine, on which rest the ends of the bridge-tree, and to which the rim A and the latter are firmly secured by bolts *b'* that pass through the rim, hubs, ends of the bridge-tree, and bed pieces C C of the machine, as clearly shown in Fig. I. E is a pinion, and F a spur-wheel, both mounted on the same shaft and supported in the rotating frame, the pinion gearing with the rim A and the wheel F meshing with a pinion, G, on the central shaft H. This shaft has its lower bearing in the bridge-tree and its upper one in a suitable cross-piece within the rim A. The bridge-tree and rim A being of cast-iron and firmly secured together the bearings for the central shaft are thereby rigidly held in the same relative position, while the bridge-tree, by connecting the bed pieces C C, braces and holds them rigidly, and prevents any springing of the parts, and the consequent strain and binding of the gearing.

I claim as my invention—

1. The bridge-tree B provided with socketed arms, combined with the central shaft H and toothed rim A cast with hubs *a a*, substantially as hereinbefore set forth.
2. The bolts *b'*, rim and hubs *A a a*, bridge-tree B, and bed pieces C C, arranged substantially as hereinbefore set forth.

JOHN VALENTINE.

Witnesses:

EDWARD WILHELM,
JOHN J. BONNER.
